CLAIM

The ornamental design for a frame for a display stand, as shown and described.

DESCRIPTION

FIG. 1 is a right perspective view of a frame for a display stand showing my new design;

FIG. 2 is a front view thereof;

FIG. 3 is a rear view thereof;

FIG. 4 is a right side elevational view thereof; the opposite side being a mirror image of the shown;

FIG. 5 is a top plan view thereof; and,

FIG. 6 is a bottom plan view thereof.
